UNITED STATES PATENT OFFICE.

ALBERT B. W. BARTHOLOMEW, OF MONTREAL, QUEBEC, CANADA.

WRITING INSTRUMENT.

Application filed June 16, 1923. Serial No. 645,890.

My invention although possessing certain features adaptable broadly to both fountain pens and propelling pencils is particularly applicable to the latter group.

Propelling pencils of the well-known makes now in use are objectionable for the reason that when one of the pieces of lead or graphite has been completely used it is necessary to dismember the pencil in order to place another piece of lead or graphite in position for writing and this dismembering proves not only vexatious to the writer but in addition causes a considerable loss of time.

The object of the present invention is to overcome this defect by providing a pencil having a magazine from which a plurality of pieces of lead or graphite may be successively fed or propelled to the writing point until the magazine is emptied, without dismembering the pencil in any way.

A further object is to provide lead propelling or feeding means which will propel or feed each piece of lead at a comparatively slow speed towards the writing point and when the lead has been completely used and the feeding movement has been completed will return rapidly to its initial position to commence another feeding movement.

Another object is to accomplish the foregoing operations by the manual rotation in one direction of the usual cap on the top of the pencil.

For full comprehension, however, of my invention reference must be had to the accompanying drawings in which similar reference characters indicate the same parts, and wherein:

Figure 1 is a longitudinal sectional view of a pencil constructed according to my invention;

Figure 2 is a transverse sectional view taken on line 2—2 Figure 1;

Figure 3 is a transverse sectional view taken on line 3—3 Figure 1 and drawn to a larger scale;

Figure 4 is a transverse sectional view

taken on line 4—4 Figure 1 and drawn to a larger scale;

Figure 5 is a transverse sectional view taken on line 5—5 Figure 1 and drawn to a larger scale;

Figure 6 is a transverse sectional view taken on line 6—6 Figure 1 and drawn to a larger scale;

Figures 7 and 8 are fragmentary longitudinal sectional views partly in elevation;

Figure 9 is a detail view of the device for propelling the lead;

Figure 10 is an underside plan view of the means for ejecting the lead from the magazine;

Figure 11 is a side elevation of the ejecting means; and

Figure 12 illustrates a modification.

Referring to the accompanying drawings the hollow cylindrical case of the pencil is indicated at 2, the tapered point at 3 and the detachable cap on the opposite end at 4. The point is constituted by a member of solid cross-section which extends into the case as at 5 with a snug fit and is bored axially as at 6 to provide a passageway for the lead, the inner end of the passageway being flared as at 7 to facilitate the entry of the lead from the magazine. The latter consists of a hollow cylindrical member 8 the interior of which is divided into an annular series of longitudinal pockets 9 having discharge openings 10 in the transverse wall 12 closing the lower end of the member. The latter is inserted into the upper end of the case and extends inwardly to the inner end of the member 5, its upper end protruding slightly beyond the top of the case and reduced and threaded as at 30 to receive the cap 4 which is internally threaded. Each of the pockets 9 is adapted to contain one of the pieces of lead 13 as indicated in Figure 1, and the discharge therefrom to the bore 6 is controlled by a distributor in the form of a toothed disc 14 which is rotatably mounted upon the reduced lower end of the magazine as at 15 in position closing the

discharge openings 10, the outside diameter of the disc being preferably greater than that of such lower end. This wheel has an opening 16 which is adapted to successively register with the openings 10 as the disc is rotated for the purpose of permitting the lead to drop therethrough into the flared mouth of the passageway 6. Although the lead will drop into the passageway by gravity it is desirable that means be provided for effecting a positive ejection and to this end an ejector is mounted within the cap 4 at the upper end of the magazine. This ejector consists of a plate 40 which is adapted to bear against the inner side of the top of the cap and a resilient inverted cup-like member 42 divided radially into a plurality of spring sections each carrying an ejecting rod 43 which is adapted to extend downwardly into one of the pockets and yieldingly bear upon the piece of lead therein, the pressure on the latter causing it to be injected into the passageway when the opening 16 registers with the pocket. The disc 14 is only rotated after the piece of lead from the preceding pocket has been used and the extent of each rotary movement is just sufficient to bring the opening 16 in alignment with the discharge opening of the next pocket. This rotary movement is caused by a cam 17 carried by an axially movable lead feeding member 18, the cam having an inclined face which is adapted to engage one of the teeth of the disc 14 each time the member 18 completes its return movement away from the point after the preceding piece of lead has been used, the construction and arrangement of the cam and the teeth of the disc being such that the disc is just moved sufficiently to move to the opening into alignment with the succeeding discharge opening.

The means for feeding or propelling the lead axially through the passageway 6 comprises a propelling element constituted by the spirally grooved periphery 19 of the magazine cylinder 8, and the member 18 which is the propelled element. The latter is of U-form having straight parallel guiding arms 22 and 23 which straddle the magazine 8 and slide axially in longitudinal guideways 24 and 25 on the case 2, and a straight diametrically disposed crotch 20 in the form of a bar which is adapted to travel within a transverse slot 21 in the member 5 and engage the inner end of each piece of lead during the feeding movement, the bar carrying the cam 17 to position to engage the teeth of the distributor disc. The groove in the periphery of the member 8 is endless and comprises two spirals 26 and 27, the former advancing from the outer end of the member towards the opposite end in a counterclockwise direction with a slow pitch (approximately nine turns to the inch)

and the latter advancing in a similar manner but in a clockwise direction with a more rapid pitch (approximately one turn to the inch). The ends of these spirals are joined together to form an endless groove which will cause slow travel in one direction but rapid travel in the opposite direction when the member 18 is rotated. The operative connection between the propelling element thus formed and the feed member 18 is accomplished by pivotally mounting a tongue 28 upon the free end of the arm 20 in position in which it will extend into the groove 19 the dimensions of the tongue being such that it will travel easily in both spirals without jamming.

Operation.

To fill the magazine the cap 4 is unscrewed and a piece of lead inserted into each pocket. The cap is then replaced.

As the opening 16 will be in position registering with one of the pockets the lead inserted into that pocket will drop through the opening to its axial position within the passageway with its inner end located just beneath the feed bar 20, it being assumed that the latter is in its uppermost position.

With the lead in position the cap is manually rotated in a clockwise direction. This rotation being imparted to the propelling member 8, causes the tongue 28 to travel along the spiral 26 towards the point of the pencil moving with it the feed member 18 and consequently feeding the lead along the passageway until it reaches the writing position, protruding slightly beyond the point. This feeding movement may be continued, as the lead is used, until the tongue reaches the inner end of the spiral 26 at which point it will enter the spiral 27. As the clockwise rotation is continued this spiral 27 through the tongue rapidly returns the feeding member to its starting position and just before this position is reached the cam 17 moving with the feeding member engages the distributor disc 14 and causes the release of another piece of lead. The foregoing operation is then repeated.

The pencil hereinbefore described illustrates but one embodiment of my invention and it is to be understood that the construction may be modified without departing from the spirit of the invention. For instance the "slow feed and quick return" feature may be applied to some of the well-known propelling pencils or self-filling fountain pens now on the market. Figure 12 illustrates the application of this feature to the well-known Eversharp pencil, the case 2 of the pencil being internally grooved to provide an endless groove constituted by spirals 26 and 27, the latter having a more rapid pitch than the former. The internal construction of the Eversharp pencil is well-known and is therefore not fully described

or illustrated, only those parts associated with the present invention being shown in dotted lines, namely the lead container which is indicated at 40¹ divided longitudinally by a transverse opening 41¹ within which a nut 42¹ moves axially. In the present case the dimensions of the latter should be such that it will readily travel in both grooves 26 and 27 without jamming. Axial movement of the nut causes the propulsion of the lead through the tapered point of the pencil case. It may be found desirable to pivot the nut so that it will more readily follow the spiral 27.

15 When applied to fountain pens the double spiral groove would be employed for the purpose of discharging and filling the ink reservoir within the pen.

What I claim is as follows:

20 1. In a mechanical pencil having a passageway for leads, a longitudinally movable element for propelling leads in said passageway, and rotary means operatively connected to the said element, said rotary means being constructed and arranged to be rotated in one direction and when so rotated to successively move the said element towards and away from the writing point without the aid of extraneous means.

25 30 2. In a mechanical pencil having a passageway for leads, a longitudinally movable element for propelling leads in said passageway, and a rotary element having an endless helical groove comprising a helical groove advancing in a counter-clockwise direction and a second helical groove advancing in a clockwise direction, the ends of one groove being respectively connected to the corresponding ends of the other, said longitudinally movable element being adapted to travel within the said endless groove whereby rotation of the rotary element causes longitudinal movement of the longitudinally movable element successively towards and away 45 from the writing point.

35 3. In a mechanical pencil having a passageway for leads, a longitudinally movable element for propelling leads in said passageway, and a rotary element having an endless helical groove comprising a helical groove advancing in a counter-clockwise direction and a second helical groove advancing in a clockwise direction, the ends of one groove being respectively connected to the corresponding ends of the other, and the pitch of one groove being wider than the pitch of the other, said longitudinally movable element being adapted to travel within the said endless groove whereby rotation of the rotary element causes longitudinal movement of the longitudinally movable element successively towards and away from the writing point.

40 45 4. A mechanical pencil having a passageway with a flared end, a cylindrical magazine having a plurality of longitudinally dis-

posed pockets adapted to contain a plurality of marking units, each pocket having a discharge opening located above the flared end of the passageway, means controlling the discharge openings, said means consisting of a rotary toothed disc having an opening 50 adapted to successively register with each of the discharge openings when the disc is rotated, means for propelling the marking units through said passageway, and means 55 for rotating the disc a predetermined extent when the propulsion of each marking unit has been completed.

5. In a mechanical pencil, a cylindrical magazine adapted to contain a plurality of marking units and having a discharge opening, and resilient means for imparting to said units a tendency to move towards the said opening.

6. A mechanical pencil consisting of a hollow cylindrical case with a tapered end having a discharge opening, the opposite end of the case being open, a rotary cylindrical member disposed longitudinally within the case adjacent the said open end of the latter, 90 the interior of the said member being divided into a plurality of pockets forming a magazine for a plurality of marking units, the exterior of said member having an endless helical groove therein comprising a helical groove advancing in a counter-clockwise direction and a second helical groove advancing in a clockwise direction, the ends of one groove being respectively connected to the corresponding ends of the other, means for 95 successively ejecting the units from the magazine, and means for propelling each unit through said discharge opening after being ejected from the magazine, said means including a longitudinally movable element 100 adapted to travel within said endless groove.

7. In a mechanical pencil, a cylindrical magazine divided longitudinally into a plurality of pockets each adapted to contain a marking unit and each having a discharge opening, and resilient means for exerting pressure upon each unit towards the discharge opening of its respective pocket independently of the other units.

8. In a mechanical pencil having a passageway for leads, a longitudinally movable element for propelling leads in said passageway, a rotary element operatively connected to the first mentioned element, said elements being so constructed and arranged that rotation of the rotary element in one direction causes longitudinal movement of the longitudinally movable element alternately in opposite directions, a magazine adapted to contain a plurality of marking leads, and means 110 in operative relation with the longitudinally movable element for successively releasing the leads from the magazine.

9. In a mechanical pencil having a passageway for leads, a longitudinally movable

element for propelling leads in said passage-way, a rotary element operatively connected to the first mentioned element, said element being so constructed and arranged that rotation of the rotary element in one direction causes longitudinal movement of the longitudinally movable element successively in opposite directions, a rotary cylindrical mag-

azine adapted to contain a plurality of leads, and means in operative relation with the longitudinally movable element for successively releasing the leads from the magazine. 10

In testimony whereof I have signed my name to this specification at Montreal this 28th day of May, 1923.

ALBERT B. W. BARTHOLOMEW.
